UNITED STATES PATENT OFFICE

92,067

DESIGN FOR A STERILIZER CABINET FOR BARBERS' TOOLS

John J. Ellis, Oakdale, Calif.

Application September 21, 1933, Serial No. 49,303

Term of patent 14 years

To all whom it may concern:

Be it known that I, JOHN J. ELLIS, a citizen of the United States, residing at Oakdale, in the county of Stanislaus, and State of California, have invented a new, original, and ornamental Design for a Sterilizer Cabinet for Barbers' Tools, of which the following is a specification, reference being had to the accompanying drawing, forming part thereof,

Figure 1 is a perspective view of a sterilizer cabinet showing my new design.

Figure 2 is a top plan view of the same on a reduced scale.

I claim:

The ornamental design for a sterilizer cabinet for barbers' tools, as shown and described.

JOHN J. ELLIS.
